US00D780261S

(12) **United States Design Patent** (10) **Patent No.:** **US D780,261 S**
(45) **Date of Patent:** **** Feb. 28, 2017**

(54) **VERTICALLY-ORIENTED TRANSACTION DEVICE**

(75) Inventors: **Kathleen H. Witsil**, Wilmington, DE (US); **Dori K. Skelding**, Wilmington, DE (US); **Rachana V. Bhatt**, Media, PA (US)

(73) Assignee: **JPMorgan Chase Bank, N.A.**, New York, NY (US)

(**) Term: **14 Years**

(21) Appl. No.: **29/425,015**

(22) Filed: **Jun. 19, 2012**

Related U.S. Application Data

(63) Continuation of application No. 29/369,093, filed on Sep. 2, 2010, now Pat. No. Des. 663,354.

(57) **CLAIM**

The ornamental design for a vertically-oriented transaction device, as shown and described.

DESCRIPTION

FIG. 1 is a front perspective view of a first embodiment of the vertically-oriented transaction device showing our new design;

FIG. 2 depicts a front elevational view thereof;

FIG. 3 depicts a back elevational view thereof;

FIG. 4 depicts a side elevational view thereof;

FIG. 5 depicts an opposite side view thereof;

FIG. 6 depicts a bottom plan view thereof;

FIG. 7 depicts a top plan view thereof;

FIG. 8 is a front perspective view of a second embodiment of the vertically-oriented transaction device;

FIG. 9 depicts a front elevational view thereof;

FIG. 10 depicts a back elevational view thereof;

FIG. 11 depicts a side elevational view thereof;

FIG. 12 depicts an opposite side view thereof;

FIG. 13 depicts a bottom plan view thereof; and,

FIG. 14 depicts a top plan view thereof.

The broken lines are shown for the purpose of illustrating portions of the article that form no part of the claimed design.

The logos forming part of the claimed design are registered trademarks of Visa International Service Association and MasterCard International Incorporated.
